ENVELOPE FOR FILING PURPOSES
AND THE LIKE

Charles A. Pate, Lufkin, Tex.

Application November 16, 1945, Serial No. 629,181

4 Claims. (Cl. 129—20)

1

This invention relates to an envelope of novel construction, and more particularly to an envelope for containing reference papers or the like and provided with means whereby it may be bound or otherwise secured into a permanent or semi-permanent file while providing ready access to the contents thereof, and to the remainder of said file.

One of the objects of the invention is to provide an envelope capable of receiving a variety of papers, photographs or similar material such as may properly accumulate in a file such as a legal file, which may be attached to such a file while permitting ready access both to its own contents and to the other contents of said file, which protects the papers and other material from accidental disclosure, and which also provides a large and unobstructed area on the front thereof whereon a list or other description of its contents may be made.

Another object of the invention is to provide an envelope formed from a single blank of paper or other sheet material of such configuration that when the various component areas thereof are folded over upon themselves or each other and suitably secured together they form an envelope open only along one edge provided with a releasable closure flap for said opening, and provided also with a pocket-like extension at an edge adjacent said closure flap communicating with the interior of said envelope.

A further object is to provide an envelope of this character which is provided with means whereby it may be attached in a file such as a law file, and particularly such an envelope wherein the pocket-like extension is adapted for such attachment.

Other objects and advantages will be apparent from the following description, the accompanying drawings, and the appended claims.

In the drawings, in which a preferred embodiment of the invention is illustrated, and in which like reference characters designate like parts throughout—

Fig. 1 illustrates a blank of paper or like material suitable for use in forming an envelope embodying the invention;

Fig. 2 illustrates a complete envelope formed from the blank shown in Fig. 1; and

Fig. 3 is a diagrammatic view in perspective illustrating the operation of the envelope shown in Fig. 2 when embodied in a file.

Among the contents of most files, and particularly files in connection with law suits and the like, there is almost invariably an accumulation

2

of papers, photographs and other documents and similar items which because of their size, shape or for some other reason cannot or should not be physically fastened in the file. For example, in a law file papers and data frequently accumulate which should be readily available but not readily open to inspection, such as papers prepared but not yet filed, early drafts of papers and the like. Such papers should be immediately available in the file but at the same time should not be subject to the direct view of an opposing party upon casual inspection of the file. The present invention is concerned with the provision of envelope means whereby such material may be secured in its proper place in a file but at the same time will remain hidden except at the will of the proper party. The invention also provides such envelope means which will in no way hamper the normal use of the file as by undue bulk or otherwise.

In the preferred embodiment of the invention shown in the drawings, the blank from which the envelope is formed may comprise heavy paper such as manila paper, a moderately thin grade of cardboard, or other suitable reasonably flexible sheet material. The material may be opaque, or for some uses of the invention it may be desirable to use a clear or colored transparent material such for example, as regenerated cellulose, cellulose acetate or the like. The blank shown in Fig. 1 comprises two main body portions 10 and 12 which form the front and back respectively of the finished envelope and are provided with an intermediate fold line 14. Back portion 12 is provided with an outwardly extending flap 15 which forms the closure means for the finished envelope. Along one of the sides adjacent flap 15, body portions 10 and 12 are provided with continuous extensions 16 and 18 which are integral therewith but are shown in Fig. 1 as set off by dotted line 17 for convenience of illustration and explanation. As shown, extensions 16 and 18 are of the same width as body portions 10 and 12 and similarly connect with each other at fold line 14. Extension 16 has a short flap 20 extending outwardly therefrom in the direction opposite from flap 15. Extension 16 also carries a further flap 22 extending in a direction at right angles to 15 and 20, and front portion 10 carries a similar flap extending in the opposite direction from flap 22. Each of flaps 20, 22 and 24 may conveniently be provided with a suitable conventional adhesive coating as indicated at 25. Fig. 2 illustrates the various component parts

of the blank in Fig. 1 combined to form the finished envelope. Body portions 10 and 12 are folded into superimposed relation along fold line 14, and flaps 20, 22 and 24 are then folded over and secured by the adhesive thereon to the back of back portion 12. The resulting envelope is open only along that portion of the edge of back portion 12 which carries flap 15, and the latter is preferably provided with a releasable fastener means, such as a pronged fastener or the cord and button assembly indicated at 26, or it may be provided with adhesive for more permanent fastening. At the same time, extensions 16 and 18 of the main body portions provide a pocket-like extension on the envelope which communicates with the interior of the latter and can be reached only through the opening at flap 15. The edge of front portion 10 which is adjacent flap 15 in the completed envelope is preferably scalloped as indicated at 28 to facilitate access to the interior of the envelope, and for most uses it has been found convenient for the blank to be so assembled that flap 15 will be on the right hand edge of the envelope as shown in Fig. 2. Back portion 12 and extension 18 thereon are preferably formed at their outer ends slightly shorter than portions 10 and 16, as indicated at 30; this construction provides clearance at the fold lines for flaps 22 and 24 and makes less bulky the connection of the latter to back portion 12.

Fig. 2 shows a pair of spaced apertures 32 adjacent the upper margin of the envelope which are adapted to cooperate with suitable fastener means such as are conventionally employed in securing together the component papers of a file. These apertures may be cut out at the same time as the initial blank, as indicated in dotted lines in Fig. 1, or they may be cut in the finished envelope. In either case they are preferably located within the outline of flap 22, which is a portion of the envelope composed of at least three thicknesses of the component material and will accordingly afford considerable resistance to tearing in use.

The proportions of the various portions of the blank shown in Fig. 1 will in some measure be governed by the specific purposes to which the finished envelope is to be put. A size of envelope found satisfactory in practice for use in a law file has front and back portions 10 and 12 measuring approximately $8\frac{3}{4}$ " by $11\frac{1}{8}$ " exclusive of extensions 16 and 18, and a satisfactory size for each of the latter is $8\frac{3}{4}$ " by $2\frac{1}{4}$ ". This construction provides pocket space ample for accommodation of conventional $8\frac{1}{2}$ " by 13" legal paper and still leaves adequate clearance for fastener elements engaging in apertures 32 without making the envelope too long for ready inclusion in a file. At the same time, since extensions 16 and 18 provide clearance between the upper edge of the envelope and flap 15, the latter may readily be opened when the envelope is bound in a file without interference with or from other papers mounted on top thereof and folded back to provide access to said envelope, as indicated at 33 in Fig. 3. Furthermore, the clearance provided by this construction at the upper end of the envelope facilitates access to other papers in the file. That is to say, when the envelope is mounted in a file it may itself be readily folded back to provide convenient access to other papers mounted thereunder in the same file.

The above construction provides ample space on the outer surface of portion 10 on which to list or otherwise indicate on the envelope the nature

of its contents. Since flaps 20, 22 and 24 which secure portions 10 and 12 together are all folded to the back of the envelope, this leaves unobstructed the front surface thereof, and a series of guide lines 34 is shown in Fig. 2 for such listing of the contents of the envelope. The particular arrangement of such guide lines will depend upon the use to which the envelope is to be put, and the showing in Fig. 2 is accordingly merely illustrative. The size and proportions of the component parts of the blank and finished envelope may also be varied in accordance with the use to which the envelope is to be put and the nature of the material to be filed therein without departing from the scope of the invention. As a general rule in such modifications it has been found satisfactory to make the overall length of the envelope at least of the order of 1" longer than the maximum length of its normal contents and to form the extensions on the envelope body portions at least of the order of 2" in length.

While the form of article herein described constitutes a preferred embodiment of the invention, it is to be understood that the invention is not limited to this precise form of article, and that changes may be made therein without departing from the scope of the invention which is defined in the appended claims.

What is claimed is:

30. 1. A filing envelope adapted to receive material of a predetermined maximum length to be fastened in a file of papers comprising a blank of sheet material forming rectangular front and back portions connected by a fold line, a flap portion extending outwardly from the edge of said back portion opposite said fold line, a second flap extending outwardly from an edge of said front portion adjacent said fold line, a continuous extended portion along the edges of both said front and back portions opposite said second flap and of substantially the same width as said front and back portions together, a third flap extending outwardly from said extended portion of said front portion in the opposite direction from said second flap, a fourth flap extending outwardly from said extended portion of said front portion in a direction at right angles to said second and third flaps, said front and back portions and said extended portions thereof being folded along said fold line into superimposed relation, said second, third and fourth flaps being folded back from said front portion and secured to said back portion to form an envelope open only along the edge of said back portion carrying said first flap but including a pocket-like extension formed by said extended portions and the flaps thereon and communicating with the interior of said envelope, said first flap being folded over said front portion to form a closure for said envelope, and means for releasably securing said first flap to said front portions, said extended portions of said envelope including means for securing said device in a file, the total length of said envelope including said extension thereon being at least of the order of 1" longer than said maximum length of said normal contents thereof and said extended portion being at least of the order of 2" in length to provide for mounting said envelope in a file by means of said securing means without materially reducing the capacity of the compartment therein and without materially affecting the opening and closing of said closure flap.
60. 2. A filing envelope adapted to be fixed in a bound file of papers to receive miscellaneous material, comprising a blank of sheet material form-

ing rectangular front and back portions connected by a fold line, a flap portion extending outwardly from the edge of said back portion opposite said fold line, a second flap extending outwardly from an edge of said front portion adjacent said fold line, a continuous extended portion along the edges of both said front and back portions opposite said second flap and of substantially the same width as said front and back portions together, a third flap extending outwardly from said extended portion of said front portion in the opposite direction from said second flap, a fourth flap extending outwardly from said extended portion of said front portion in a direction at right angles to said second and third flaps, said front and back portions and said extended portions thereof being folded along said fold line into superimposed relation, said second, third and fourth flaps being folded back from said front portion and secured to said back portion to form an envelope open only along the edge of said back portion carrying said first flap but including a pocket-like extension formed by said extended portions and the flaps thereon and communicating with the interior of said envelope, said first flap being folded over said front portion to form a closure for said envelope, and means for releasably securing said first flap to said front portions, said extended portions of said envelope including flexible means for securing said envelope in a file providing for unobstructed access to the remaining papers in said file, said last named means including at least one aperture through the triple layered portion of said envelope composed of said third flap and said extended portions of said body portions.

3. An envelope adapted to be fastened in a file of papers to contain and protect material of miscellaneous sizes while permitting easy insertion and withdrawal of said material into and out of said envelope without removal of said envelope from said file, comprising generally rectangular front and back body portions of sheet material superimposed upon each other and secured together along the entire length of one pair of the longer edges of said body portions and of both of the shorter edges thereof to form an envelope pocket, the other pair of longer edges of said body portions being unsecured from one of their ends for the greater portion of their length and being secured together from their other end for a relatively short portion of their length to provide a closed portion of said envelope pocket forming an extension for binding said envelope in a file of papers, said back body portion having a flap extending along said unsecured edge portion thereof substantially co-extensive with said

unsecured edge portion and adapted to fold over said front body portion to close said envelope pocket, said binding extension also forming a pocket communicating internally with said envelope pocket to provide for insertion in said envelope of material longer than said envelope pocket, and said binding extension containing at least one aperture to receive fastener means for securing said envelope in a file of papers.

4. A filing envelope adapted to be fixed in a bound file of papers to receive miscellaneous material, said miscellaneous material forming part of said file but not to be fastened therein, to provide ready access to said miscellaneous material without concealing or disturbing other papers in said file, comprising generally rectangular front and back body portions of sheet material superimposed on each other by a fold along a common edge thereof, flaps along substantially the entire length of the two edges of said front body portion adjacent said fold folded over and fixed to said back body portion to form a pocket, a further flap on said front body portion on the edge opposite said fold extending a relatively short distance from one corner thereof and folded over and fixed to said back body portion to form a binding extension at one end of said pocket, the pocket within said binding extension communicating with the remaining portion of said pocket, said binding extension having apertures to receive fasteners for retaining said envelope in a file of papers, said back body portion having a flap on the edge thereof opposite said folded edge extending substantially along the open portion thereof and adapted to be folded over said front body portion, said flap being relatively narrow to facilitate ready opening and closing of said pocket when said envelope is fastened in a file of papers and to leave the outer face of said front body portion substantially unobstructed for recording the contents of said envelope, and means for releasably securing said flap to said front body portion.
